UNITED STATES PATENT OFFICE.

CHARLES E. SMITH, OF NEW YORK, N. Y., ASSIGNOR TO UNDERWOOD TYPEWRITER COMPANY, OF NEW YORK, N. Y., A CORPORATION OF DELAWARE.

PAGE-END LOCK FOR TYPE-WRITERS.

1,169,577.

Specification of Letters Patent. Patented Jan. 25, 1916.

Application filed March 19, 1913, Serial No. 755,369. Renewed July 11, 1914. Serial No. 850,351.

To all whom it may concern:

Be it known that I, CHARLES E. SMITH, a British subject, residing at New York, in the county of New York and State of New York, have invented new and useful Improvements in Page-End Locks for Type-Writers, of which the following is a specification.

The object of this invention is to provide 10 a typewriter attachment, known in the art as a "page-end lock", which shall be simple in construction, which may be applied to any typewriter on the market, and which is thoroughly efficient for the purposes intended, *i. e.*, to lock the typewriter platen against movement at a predetermined stage or period in the line-spacing movement of the typewriter, so that a predetermined margin on the lower end of the typewriting sheet 20 may be maintained.

Another object of the invention is to provide means for locking the platen against line-spacing movement, at variable predetermined periods or stages in the line-spacing movement of the typewriter.

Another object of the invention is to provide means, operative when the page-end locking mechanism becomes initially active, to indicate, visually, to the operator how 30 many line-spacing movements of the typewriter will take place before the page-end locking mechanism will finally lock the platen against any further movement.

With these objects in view, and others 35 appearing as the specification proceeds and the nature of the invention more fully appears, the invention resides in the novel construction, combination and arrangement of parts, as fully hereinafter described in the 40 specification, summed up in the claims, and illustrated in the drawing.

In the accompanying drawing, I have 45 illustrated, as an example merely, a form of embodiment of my invention capable of carrying out the underlying principles thereof; it being understood, of course, that the exemplified form is susceptible of many changes, without departing from the spirit of the invention or sacrificing any of its advantages, and that all such changes as come 50 within the scope of the appended claims are within the purview of this application.

In the accompanying drawing, in which like reference-characters denote correspond-

ing parts throughout the several views: 55 Figure 1 is a fragmentary perspective view of so much of a typewriter as is necessary to an understanding of the device of my invention, which is shown applied thereto; Fig. 2 is a transverse section of Fig. 1, showing the page-end locking mechanism in inoperative position; Fig. 3 is a view similar to Fig. 2, but showing the page-end locking mechanism in operative position; Fig. 4 is a sectional detail view of the rack and the 65 adjustable pointer-carrying stop carried thereby; and Fig. 5 is a detached perspective detail view of said adjustable stop.

Referring, now, in detail to the drawing: 70 1, 1 designate end supports, in which the shaft 2 of the typewriter platen 3 is rotatably journaled, as usual. These parts form no portion of my invention, and are well known in the typewriter art, and, therefore, need no detailed description. 75

The platen-shaft 2 carries fast thereon, at one end thereof, in this instance the right-hand end, a gear-wheel 4, adapted to mesh with a rack 5, which, in this instance, is reciprocably mounted, so as to slide longitudinally, on a rod 6, which may be pivoted, at the front end thereof, as shown at 7, to the right-hand end support 1. The rod 6 may carry a suitable stop 8 to limit movement in one direction, that is, forward movement of the rack 5. The rack 5 is preferably provided, on its top, with a longitudinally-extending groove 9, in which is slidably carried a screw-member 10. On the portion of the threaded shank of said screw-member 90 10 which projects out of said groove 9 is screwed an internally-threaded cap 11, carrying a pointer 12, registering with a scale 13, comprising numbers printed or painted on the top of the right-hand end 95 support 1, and extending longitudinally thereof. It will be evident that, by revolving, in one direction, the cap 11 on the threaded shank of the screw-member 10, the latter may be frictionally clamped against 100 movement to the rack 5, and that, by a reverse rotation of said cap, said screw-member 10 will be loosened from its frictional engagement with the rack 5, and may, then, be shifted, in the groove 9, longitudinally of 105 said rack. In this manner, said pointer-carrying member 11 is adjustably secured to and carried by said rack. It will also be

5 noted that the adjustable pointer-carrying member may be said to consist of two parts, the cap 11 and the screw 10. While the specific form of adjustable pointer-carrying member so shown in the drawing and described in the specification is an example of a practicable form, yet it is to be understood that such exemplified type is susceptible of modification, without departing from the 10 spirit of my invention, or sacrificing any of its advantages.

One end of a coiled spring 23 is secured to the rack 5 and the other end of said spring to the rod 6.

15 A stop 24 may be carried by the right-hand end support 1, to be engaged by the adjustable pointer-carrying stop 11 at the proper period in the rearward reciprocation of the rack 5.

20 The typewriter paper-shelf 14 is provided, preferably toward its lower end, with a series of longitudinally-extending apertures 15, registering with which are feelers in the form of anti-friction rollers 16, carried by a rod 17, which is, in turn, carried, at its ends, by crank-levers 18, 18, projecting through apertures 19, 19, in said paper-shelf 14, and fulcrumed to the latter in the 25 region of said apertures, as shown at 20, 20. Said crank-levers 18, 18 may conveniently carry, at their otherwise free extremities, or upper ends, handles or knobs 21, 21, for ready manipulation thereof. The rod 17 carries, at the end thereof nearest the rack 5, an upwardly curved projecting arm or leg 22, the free upper end of which is adapted to engage the under surface of the rack 5, as shown in Figs. 1 and 2.

25 indicates a sheet of typewriting paper 40 in operative position upon the typewriter platen 3.

Operation: In operation, when it is desired to insert a sheet of typewriting paper 25 in operative position on the platen 3, 45 the operator presses downward upon the handles 21, which rocks the crank-levers 18, 18 on their fulcrums 20, 20, and moves the rod 17, with its rollers 16, in a direction away from the paper-shelf 14, said 50 rollers being thus caused to move out of the apertures 15. The paper 25 may then be slipped between said rollers 16 and the paper-shelf 14; thereupon, the handles 21 are released and the rollers 16 fall back 55 upon the paper 25, which prevents the rollers from falling into said apertures 15 until, in the line-spacing movement of the typewriter, the paper 25 moves from beneath said rollers. It will be noted that, 60 as long as the rollers 16 are in engagement with the paper 25; *i. e.*, as long as the paper 25 is interposed between said rollers and the paper-shelf 14, the arm 22 will be raised into engagement with the rack 5, lifting the latter as shown in Figs. 1 and 2 (most clearly

in the latter), out of engagement with the gear-wheel 4. The parts of the page-end locking mechanism will now be in the position shown in Figs. 1 and 2. As soon, however, as the bottom portion of the paper 25 (in the course of the line-spacing movement of the typewriter) passes from beneath the rollers 16, the crank-levers 18, 18 will, by reason of the weight of the rollers 16, the rod 17, and the arm 22, rock on their fulcrums, causing the rollers 16 to move into the apertures 15. This movement will, of course, release the arm 22 from engagement with the rack 5, which, by gravity, falls downward on its pivot 7, into engagement with the gear-wheel 4. Thereafter, every movement of the line-spacing mechanism of the typewriter, to rotate the platen 3, will cause the rack, by reason of its engagement with the gear-wheel 4 carried fast on the platen-shaft 2, to move rearward, against the tension of the spring 23, until the adjustable pointer-carrying stop 11 engages the stationary or fixed stop 24, at which time further rotation of the platen, by the line-spacing mechanism of the typewriter, will be prevented, and the platen will thus be locked against movement. This will indicate to the operator that the end of the page 25 has been reached. When the page 25 has 95 been withdrawn from the platen and another sheet inserted, the arm 22 will once more engage and raise the rack 5 out of engagement with the gear 4, whereupon the spring 23 will automatically pull the rack 5 forward to initial position, *i. e.*, into engagement with the stop 8.

As will be seen, the adjustable pointer-carrying stop 11 may be set at any desired point on the rack-bar 5, within the limits of the slot 9, so that the locking of the platen may be effected at varying points, after the page-end locking mechanism becomes initially operative, by reason of the engagement of the rack 5 with the gear-wheel. 105

The scale 13, in connection with the pointer 12, indicates to the operator how many line-spacing movements of the platen may be effected, after the rack 5 engages the gear wheel 4, before the platen becomes locked against movement. Thus, in Fig. 1, the adjustable pointer-carrying member or stop 11 is set so as to cause the pointer to register with the number 5 of the scale 13. This indicates to the operator that, after the 110 rack 5 engages the wheel 4, five line-spacing movements of the platen 3 may be effected before the platen becomes locked against movement. Of course, two scales 13 might be provided, one scale with the numbers 115 nearer together than the other scale, to correspond with half-spacing movements of the platen, as will be readily understood.

With the above detailed description, taken in connection with the drawing, the many 120

advantages of my invention will be apparent, especially to those skilled in the art to which this invention appertains.

Having thus fully described my invention, 5 what I claim as new, and desire to secure by Letters Patent of the United States is:

1. In a page-end lock for typewriters, a platen-shaft; a gear-wheel carried fast thereon; a rack engageable with said gear-wheel and having a longitudinally extending groove therein; and means for arresting movement of said rack at a predetermined period after engagement thereof with said gear-wheel, comprising a stop adjustably 15 positioned in said groove.

2. In a page-end lock for typewriters, a platen-shaft; a gear-wheel carried fast thereon; a rack engageable with said gear-wheel and having a longitudinally-extend- 20 ing groove therein; and two co-operating stops, one thereof comprising a screw-threaded member seated in said groove and a cap-member screwed onto said screw-threaded member.

3. In a page-end lock for typewriters, a platen-shaft; a gear-wheel carried fast thereon; a rack engageable with said gear-wheel and having a longitudinally-extend- 25 ing groove therein; two co-operating stops, one thereof comprising a screw-threaded member seated in said groove and a pointer-carrying cap-member screwed onto said screw-threaded member; and a scale co-operating with said pointer.

4. In a page-end lock for typewriters, a platen-shaft; a gear-wheel carried fast thereon; a rack engageable with said gear-wheel; means for temporarily maintaining the rack out of engagement with said gear-wheel, including a member carrying rollers, 40 and an arm carried by said member and engageable with said rack; and means for arresting movement of said rack at a predetermined period after engagement thereof 45 with said gear-wheel.

5. In a page-end lock for typewriters, a platen-shaft; a gear-wheel carried fast thereon; a rack engageable with said gear-wheel; means for temporarily maintaining the rack out of engagement with said gear-wheel, comprising a member carrying rollers, an arm carried by said member and engageable with said rack, and fulcrumed 50 crank-levers carrying said member; and means for arresting movement of said rack at a predetermined period after engagement thereof with said gear-wheel.

6. In a page-end lock for typewriters, a platen-shaft; a gear-wheel carried fast 60 thereon; a rack engageable with said gear-wheel; means for temporarily maintaining the rack out of engagement with said gear-wheel, including a member carrying rollers, and an arm carried by said member and engageable with said rack; a paper-shelf pro-

vided with apertures registering with said rollers; and means for arresting movement of said rack at a predetermined period after engagement thereof with said gear-wheel.

7. In a page-end lock for typewriters, a platen-shaft; a gear-wheel carried fast thereon; a rack engageable with said gear-wheel; a paper-shelf having a series of apertures; means for temporarily maintaining the rack out of engagement with said gear-wheel, including a member carrying rollers registering with said apertures, an arm carried by said member and engageable with said rack, and crank-levers fulcrumed on said paper-shelf and carrying said member; and means for arresting movement of said rack at a predetermined period after engagement thereof with said gear-wheel. 70

8. In a page-end lock for typewriters, a platen-shaft; a gear-wheel carried fast thereon; a rack engageable with said gear-wheel; a paper-shelf having a series of apertures; means for temporarily maintaining the rack out of engagement with said gear-wheel, comprising a member carrying rollers registering with said apertures, an arm carried by said member and engageable with said rack, and crank-levers projecting through and fulcrumed on said paper-shelf and carrying said member; and means for arresting movement of said rack at a predetermined period after engagement thereof with said gear-wheel. 85

9. In a page-end indicating device, the combination with a rotatable platen, of a gear wheel connected to rotate when the platen is rotated, a rack movable bodily into and out of mesh with said gear wheel, a supporting member whereon said rack is mounted to slide bodily, and means controlled by a work-sheet for holding the rack out of engagement with said gear wheel until the work-sheet has reached a predetermined position. 95

10. In a page-end indicating device, the combination with a rotatable platen, of a gear wheel connected to rotate when the platen is rotated, a rack movable bodily into and out of mesh with said gear wheel, a supporting member whereon said rack is mounted to slide bodily, means controlled by a work-sheet for holding the rack out of engagement with said gear wheel until the work-sheet has reached a predetermined position, an index carried by said rack, and a co-operating scale. 110

11. In a page-end indicating device, the combination with a rotatable platen, of a gear wheel connected to rotate when the platen is rotated, a rack movable bodily into and out of mesh with said gear wheel, a supporting member whereon said rack is mounted to slide bodily, means controlled by a work-sheet for holding the rack out of engagement with said gear wheel until the 115

work-sheet has reached a predetermined position, and a stop for terminating the sliding movement of the rack and thereby limiting the extent of rotation of the platen permitted after said rack has engaged said gear wheel.

12. In a page-end indicating device, the combination with a rotatable platen, of a gear wheel connected to rotate when the platen is rotated, a rack movable into and out of mesh with said gear wheel, a supporting member for said rack with which the rack has a sliding connection, means controlled by a work-sheet for holding the rack

15 out of engagement with said gear wheel until the work-sheet has reached a predetermined position, a stop carried by said rack and adjustable therewith, a pointer adjustable with said stop, a graduated scale 20 over which said pointer moves, and a stop fixed with relation to said scale and in the path of said first-named stop.

13. The combination with a rotary platen and a platen frame, of a gear wheel connected to rotate when the platen is rotated, a rack movable bodily into and out of mesh with said gear wheel, a supporting member for said rack pivoted to the platen frame and with which said rack has a straight-line 30 sliding connection, and means controlled by a work-sheet to hold said rack out of engagement with the gear wheel until the work-sheet reaches a predetermined position.

35 14. The combination with a roller platen, of a gear wheel connected thereto, a rack movable into and out of mesh with the gear wheel, a pointer carried by said rack, a scale over which said pointer moves, and 40 means controlled by a work-sheet for normally holding said rack out of mesh with said gear wheel, and permitting it to move into mesh therewith when the work-sheet reaches a predetermined position.

45 15. The combination with a roller platen, of a gear wheel connected thereto, a swinging support, a rack slidably mounted thereon, means controlled by a work-sheet for holding said support and rack in inoperative 50 position with the rack out of engagement with the gear wheel, and permitting said support and rack to swing into position to engage the rack with said gear wheel when the work-sheet reaches a predetermined 55 position, a pointer carried by said rack, a scale over which said pointer moves, a stop moving with said pointer, and a counter-stop to engage said stop when the pointer reaches the zero point on the scale 60 and thereby lock the platen against further rotation.

16. In a page-end indicating device, the combination with a platen frame and a roller platen journaled thereon, of a gear 65 wheel connected to rotate with the platen,

a rack movable into and out of mesh with said gear wheel, a swinging support pivoted at its forward end to the inner face of the platen frame end, said support and rack extending rearwardly from said pivot to overhang said gear wheel, means controlled by a work-sheet to hold said rack and support in inoperative position until the work-sheet reaches a predetermined position and then permitting the rack to drop into engagement with said gear wheel, and an indicator to indicate the extent of rotation of the platen after the rack has been brought into engagement with said gear wheel.

17. In a page-end indicating device, the combination with a platen frame and a roller platen journaled thereon, of a gear wheel connected to rotate with the platen, a rack movable into and out of mesh with said gear wheel, a swinging support pivoted at its forward end to the inner face of the platen frame end, said support and rack extending rearwardly from said pivot to overhang said gear wheel, means controlled by a work-sheet to hold said rack and support in inoperative position until the work-sheet reaches a predetermined position and then permit the rack to drop into engagement with said gear wheel, an indicating pointer adjustable along the rack, a graduated scale over which said pointer moves, a stop adjustable with said pointer, and a co-operating counter-stop having a fixed relation to the said scale to engage said stop and lock the platen against further rotation when the pointer reaches a predetermined point along the scale.

18. The combination, with a platen, and a driving element connected to rotate therewith; of a rectilinearly-movable element to be driven by said driving element; and work-sheet-controlled means normally holding said driven element in ineffective relation to said driving element, and permitting said driven element to move bodily into effective relation to said driving element when the work-sheet reaches a predetermined position.

19. The combination, with a platen, and a driving element connected to rotate therewith; of a rectilinearly-movable element to be driven by said driving element; work-sheet-controlled means normally holding said driven element in ineffective relation to said driving element, and permitting said driven element to move bodily into effective relation to said driving element when the work-sheet reaches a predetermined position, and means for automatically locking said driven element at a predetermined point in its travel.

20. The combination, with a platen, and a driving element connected to rotate therewith; of a rectilinearly-movable element to be driven by said driving element; work-

sheet-controlled means normally holding said driven element in ineffective relation to said driving element, and permitting said driven element to move bodily into effective relation to said driving element when the work-sheet reaches a predetermined position; a stop carried by said driven element; and a stop engageable by the first-named stop at a predetermined point in the travel of said driven element, to lock the latter against further movement.

21. The combination, with a platen and its frame; of a driving element connected to rotate with said platen; an element to be driven by said driving element; work-sheet-controlled means normally holding said driven element in ineffective relation to said driving element, and permitting said driven element to move bodily into effective relation to said driving element when the work-sheet reaches a predetermined position; and

coöperating devices carried by said driven element and one of the members of said frame, for automatically arresting the former at a predetermined point in its travel.

22. The combination, with a platen, and a driving element connected to rotate therewith; of a rectilinearly-movable element to be driven by said driving element; and so work-sheet-controlled means normally holding said driven element above said driving element, and permitting it to drop bodily into engagement therewith when the work-sheet reaches a predetermined position. 35

In testimony whereof, I have hereunto set my hand in presence of two subscribing witnesses.

CHARLES E. SMITH.
